UNITED STATES PATENT OFFICE.

CHARLES HAYNES MASON, OF THE UNITED STATES ARMY.

COMBINED GARMENT, SHELTER-TENT, AND BLANKET-ROLL COVERING.

SPECIFICATION forming part of Letters Patent No. 766,719, dated August 2, 1904.

Application filed March 23, 1904. Serial No. 199,604. (No model.)

To all whom it may concern:

Be it known that I, CHARLES HAYNES MASON, a lieutenant in the Eighth United States Infantry, stationed at Fort Wood, New York 5 Harbor, State of New York, have invented certain new and useful Improvements in a Combined Garment, Shelter-Tent, and Blanket-Roll Covering; and I do hereby declare the following to be a full, clear, and exact description of the invention, such as will enable others skilled in the art to which it appertains to make and use the same.

My invention relates to improvements in waterproof coverings, and is especially applicable for use as a soldier's equipment on the march, but may be equally as well adapted for other than army purposes.

The object of the invention is to so construct the waterproof covering as to adapt it for use 20 as a waterproof garment or cape, tent-covering, and covering for blanket-roll or other articles.

The advantages of my invention will be apparent from the following specification, where- 25 in the points of novelty will appear and be claimed.

To more fully understand the invention, reference is had to the accompanying drawings, illustrating the same and its mode of applica- 30 tion for use, in which like characters designate like parts in the several views, and in which—

Figure 1 shows the application for use as a garment or cape; Fig. 2, its application as a covering for a blanket-roll on the march; Fig. 3, its application as a tent-covering; Fig. 4, a plan view of the covering while flat on the ground in its open and extended position; Fig. 5, a detail fragmentary view of the outer circumferential portion looking from the inside 35 face and showing the extension-flap fastened up in position, with the method of folding or creasing the outer edge of the extension-flap so as to prevent bulging when turned and secured; Fig. 6, a detail fragmentary view of the inside face of the extension-flap when 40 opened, showing the tent-peg secured thereto; Fig. 7, a sectional view on the line 7 7 of Fig. 5 looking to the left and showing the position of the tent-pegs when the extension-flap

is turned and secured. Fig. 8 shows the 50 method of folding the covering for the reception of the blanket-roll; Fig. 9, a plan view of the buckle for the fastening-straps; and Fig. 10, a transverse sectional view through the buckle, showing the manner of securing the 55 ends of the fastening-strap thereto.

1 is the main portion of the covering, composed of a plurality of sections seamed together, as shown by the dotted lines in Fig. 4, and is of a substantially circular construction 60 when spread out flat, with an angular opening formed therein, the edges of which extend from the center to the outer circular edge. These angularly-disposed edges 2 are reinforced by being hemmed and are provided 65 with a plurality of fastening means, preferably in the form of a clasp of the ball-and-socket type, 3 in the drawings representing the ball and 4 the socket members of the clasp. Around the outer circular edge of the main 70 portion 1 is an extension-flap 5, adapted to be turned and secured by suitable fastening means to the inside face of the main portion 1 when the covering is used as a cape or blanket-roll covering, but adapted to be extended when 75 the covering is to be used as a tent. At the center of the main portion 1 is arranged a hood or cap-piece 6, suitably provided with fastening means of the character heretofore mentioned and adapted to be secured and close 80 the apex of the tent when used as a tent-covering and to be unfastened and folded down to form a collar, as in Fig. 1, when used as a cape.

7 represents openings for the arms covered by the flaps 8, and a suitable pocket may also 85 be provided, as illustrated at 9.

10 represents buckles suspended on one end of the fastening-straps 11, secured to the outside of the covering and normally passing through slots therethrough covered by the 90 flaps 12. The free ends of the straps are adapted to be passed through the covering to the outside thereof when the same is to be used as a covering for the blanket-roll, as illustrated in Fig. 8, and passed through the 95 buckle in the manner indicated at Fig. 10 for adjustably but securely fastening the free ends of the straps.

13 represents openings formed around the circumferential edge of the extension-flap 5, in which openings are secured the metallic member 14, having the central transverse arms 15, forming a pivotal support for the tent-pegs 16, which are adapted to be retained in a folded position within the space formed between the extension-flap 5 and the outer portion of the main body 1 of the covering 10 when the extension-flap is inturned and secured thereto.

The fastening means for securing the outer edge of the extension-flap 5 to the inside face of the main portion 1 is preferably of the ball-and-socket type of clasp heretofore mentioned; but for the purposes of describing the manner of folding or creasing the extension-flap to prevent bulging when inturned and secured I have designated the socket and ball members as 4^a and 4^b, respectively, in Figs. 5 to 7. On each side of the socket member 4^a and located on the outside face of the extension-flap are the ball members 3^b of another pair of clasps, adapted to engage with the socket members 3^a, disposed a short distance therefrom, as clearly shown in Fig. 6, one of these clasps 3^b 3^a being shown locked in position on the left-hand side of Fig. 5 and unclasped on the right-hand side of said figure. 30 When used as a garment or cape, as illustrated in Fig. 1, the center flap 6 is unfastened and turned down, forming a collar portion, and the angular edges 2 are secured to each other, the arms passing through the opening 7.

In pitching the tent the outer edge of the extension-flap is unclasped from the main portion 1 and the tent-pegs are driven in the ground on the line of a circle having a radius 40 the length of the rifle, the covering being of such size as to adapt the use of the rifle for its center pole, or a pole other than the rifle may be used, if desired. When the pegs have all been driven in position, the cap or 45 hood 6 is securely fastened by the members 3 and 4 of the clasps thereon, and the muzzle of the rifle is inserted beneath the peak of the hood, as in Fig. 3, and upon swinging the stock inward the tent is pitched.

50 If it is desired to use the rifle for any purpose while it is being used as the tent-pole, it may be withdrawn without removing the tent-pegs, so that the tent-covering will fall on the ground in position to be readily raised and covering and protecting any such articles as may be thereunder.

When the covering is used for a cover for the blanket-roll, the extension-flap is fastened up like when worn as a cape, the front 60 being fastened also and the whole laid flat on the ground and doubled over in the position shown in Fig. 8, the straps 11 having been pulled through to the outside and the hood portion folded as shown, when the blanket-roll (indicated by *a*) may be placed in position.

The bottom of the hem portion of the covering is then first folded over the blanket-roll and the whole rolled up and the straps passed therearound and passed at their free ends through the buckles 10 in the manner illustrated in Fig. 10. 70

I do not wish to limit myself to the exact details of construction, as it is obvious that many modifications might be made without departing from the spirit of my invention; 75 but

What I claim, and desire to secure by Letters Patent of the United States, is—

1. A covering adapted for use as a combined garment and shelter-tent, comprising a substantially circular body portion having an opening therein extending from its central portion to its outer edge, in combination with foldably-mounted tent-pegs disposed circumferentially therearound, means for securing 85 said tent-pegs in a folded position, and means for securing the edges of said opening.

2. A covering adapted for use as a combined garment and shelter-tent, comprising a substantially circular body portion having an opening therein extending from its central portion to its outer edge, in combination with tent-pegs disposed circumferentially therearound, means for securing said tent-pegs in a folded position, comprising an extension-flap extending circumferentially around said body portion, means for securing said extension-flap to the inside face of said body portion in a folded position, and means for securing the edges of said opening. 90

3. A covering adapted for use as a combined garment and shelter-tent, comprising a substantially circular body portion having an opening therein extending from its central portion to its outer edge, in combination with pivoted tent-pegs disposed circumferentially therearound, means for securing said tent-pegs in a folded position, and means for securing the edges of said opening. 95

4. A covering adapted for use as a combined garment and shelter-tent, comprising a substantially circular body portion having an opening therein extending from its central portion to its outer edge, in combination with pivoted tent-pegs disposed circumferentially therearound, means for securing said tent-pegs in a folded position, comprising an extension-flap extending circumferentially around said body portion, means for securing said extension-flap to the inside face of said body portion in a folded position, and means for securing the edges of said opening. 110

5. A covering adapted for use as a combined garment and shelter-tent, comprising a substantially circular body portion having an opening therein extending from its central portion to its outer edge, in combination with an extension-flap extending circumferentially around said body portion, tent-pegs carried by said extension-flap, means for securing the 115 120 125 130

edges of said opening, and means for securing said extension-flap to said body portion in a folded position.

6. A covering adapted for use as a combined garment and shelter-tent, comprising a substantially circular body portion having an opening therein extending from its central portion to its outer edge, in combination with an extension-flap extending circumferentially around said body portion, pivoted tent-pegs carried by said extension-flap, means for closing said opening, and means for securing said extension-flap to said body portion in a folded position.

15 7. A covering adapted for use as a combined garment and shelter-tent, comprising a substantially circular body portion having an opening therein extending from its central portion to its outer edge, in combination with an extension-flap extending circumferentially around said body portion, tent-pegs pivotally carried by said extension-flap on its inner face, means for closing said opening, and means for securing said extension-flap to the inside face of said body portion in a folded position.

8. A covering adapted for use as a combined garment and shelter-tent, comprising a substantially circular body portion, provided with a central reinforced cap-piece and having an opening extending substantially centrally from said cap-piece to the outer edge of said body portion, in combination with foldably-mounted tent-pegs disposed circumferentially around said body portion, means for securing said tent-pegs in a folded position, and means for closing said opening.

9. A covering adapted for use as a combined garment and shelter-tent, comprising a substantially circular body portion provided with a central reinforced cap-piece and having an opening extending substantially centrally from said cap-piece to the outer edge of said body portion, in combination with foldably-mounted tent-pegs disposed circumferentially therearound, means for securing said tent-pegs in a folded position, comprising an extension-flap extending circumferentially around said body portion, means for securing said flap to said body portion in a folded position, and means for closing said opening.

10. A covering adapted for use as a com-

bined garment and shelter-tent, comprising a substantially circular body portion provided with a central reinforced cap-piece and having an opening extending substantially centrally from said cap-piece to the outer edge of said body portion, in combination with an extension-flap extending circumferentially around said body portion, tent-pegs carried by said extension-flap, means for securing said extension-flap to said body portion, in a folded position around said pegs, and means for closing said opening.

11. A covering adapted for use as a combined garment and shelter-tent, comprising a substantially circular body portion provided with arm-holes and covering-flaps therefor and having an opening extending from its central portion to its outer edge, in combination with foldably-mounted tent-pegs disposed circumferentially therearound, means for securing said tent-pegs in a folded position, and means for closing said opening.

12. A combined garment, shelter-tent and blanket-roll covering, comprising a substantially circular body portion having an opening extending from its central portion to its outer edge, in combination with foldably-mounted tent-pegs disposed circumferentially therearound, means for securing said tent-pegs in a folded position, means for closing said opening, and straps and locking means therefor for securing said body portion around the blanket-roll.

13. A combined garment, shelter-tent and blanket-roll covering, comprising a substantially circular body portion having an opening extending from its central portion to its outer edge, in combination with an extension-flap extending circumferentially therearound, tent-pegs carried by said extension-flap, means for securing said flap to said body portion, in a folded position around said pegs, means for closing said opening, and straps and locking means therefor for securing said body portion around the blanket-roll.

In testimony whereof I affix my signature in presence of two witnesses.

CHARLES HAYNES MASON.
